CLAIM

The ornamental design for pants, as shown and described.

DESCRIPTION

FIG. 1 is a front perspective view of pants showing my new design in an in-use configuration;

FIG. 2 is a front view thereof;

FIG. 3 is a side view thereof;

FIG. 4 is a second side view thereof;

FIG. 5 is a rear view thereof;

FIG. 6 is a top view thereof; and,

FIG. 7 is a bottom view thereof.

The broken lines immediately adjacent to the shaded area represent unclaimed boundaries of the design. The unshaded regions, demarcated by broken lines, represent unclaimed portions of the pants and form no part of the claimed design. The broken lines showing the remainder of the pants are for environmental purposes only and form no part of the claimed design. The contrast shading represents a contrast in appearance only.
